CLAIM

I claim the ornamental design for a shoe, as shown and described.

DESCRIPTION

FIG. 1 is a front, bottom perspective view of a shoe, showing my new design;

FIG. 2 is a bottom view thereof; and,

FIG. 3 is a rear, bottom perspective view thereof.

The broken line rectangles within the shaded area and broken lines therein form no part of the claimed design. The broken lines depicting the remainder of the shoe show features that form no part of the claimed design.
